UNITED STATES PATENT OFFICE.

WILLIAM E. H. BELL, OF GLENSIDE, PENNSYLVANIA, ASSIGNOR, BY MESNE ASSIGNMENTS, TO H. W. BUTTERWORTH & SONS COMPANY, A CORPORATION OF PENNSYLVANIA.

DYEING MACHINE.

Application filed November 20, 1924. Serial No. 750,984.

This invention relates to machinery for the treatment of textiles or the like, or more especially to dyeing machinery of the type employing a drum receiver mounted for rotation within the dyeing liquor.

It is an object of the invention to provide an improved mechanism of the class mentioned wherein the drum receiver or reel for the textile may be lowered or raised so as to be immersed in the liquor or to assume an elevated position so the textile goods may be readily loaded into or removed from the receiving drum.

Another object of the invention is to provide an improved mechanism of the class mentioned with a simple and satisfactory mechanism of improved design for operating the receiving drum with equal facility in either raised or lowered position.

20 A further object is to provide an improved hoisting mechanism for raising and lowering the receiver, being operated at will by coaction with the drive for the receiver.

Still another object is to provide an improved mechanism of the class mentioned which, while being durable and efficient in operation, is simple and inexpensive in construction, being arranged to facilitate loading of the goods into the receiver or removal 30 therefrom.

Other objects will be in part obvious in connection with the following detailed description of an illustrative but preferred embodiment of the invention, and will be in part pointed out therein.

The invention accordingly comprises the features of construction, combinations of elements, and arrangement of parts, which will be exemplified in the construction hereinafter set forth and the scope of the application of which will be indicated in the claims.

For a more complete understanding of the nature and objects of the invention reference should be had to the following detailed description taken in connection with the accompanying drawing, in which:

Fig. 1 is an end elevation of a dyeing machine embodying the invention;

50 Fig. 2 is a side elevation looking toward the right side of Fig. 1;

Fig. 3 is a side elevation looking toward the left side of Fig. 1; and

55 Fig. 4 is a central sectional view of Fig. 2 looking toward the right.

Referring to the drawing for a detailed description of the embodiment herein disclosed, there is provided a tank 10 for the dye or other treating liquor, being supported by a suitable frame structure including end 60 frames 11 and 12 which may conveniently be of integral cast metallic construction. The tank is preferably constructed of non-corrodible sheet metal having end walls 13 lying against the end frames and side walls 65 14 merging into the curved bottom 15 which may be provided with a conduit 16 for admitting and draining off the dye liquor. The margins of the end walls 13 preferably 70 lie in overlapping relationship with outwarded flanges of the side and bottom walls to form connecting and stiffening ribs as indicated at 17. Tie rods 18 connect the end frames 11 and 12 preferably piercing these external ribs or flanges as shown in Fig. 4. 75 A cover plate 19 overlies the top of the tank forming an entirely enclosed interior compartment.

The interior compartment of the tank is somewhat elongated in vertical dimension 80 and a doorway is arranged in elevated position at the front side of the tank, being closed by a door 20 slidably mounted in the frame for vertical movement and being counter balanced by weights 21 attached to 85 the door by cords 22 passing over pulleys 23, so it may be readily opened or closed by hand. An apron 24 of sheet metal or like material is hinged to the tank frame adjacent the doorway so as to swing inwardly 90 through the latter, or downwardly adjacent thereto, and the purpose of which is more fully disclosed below.

A receiver 25 for carrying the material under treatment is mounted for movement 95 within the tank, being arranged to be lowered into the dye liquor so as to effect thorough and even penetration of the fibers of the treated material, or to be raised into elevated position above the liquor. This receiver as shown in the embodiment of the drawings preferably takes the form of a cylindrical drum mounted for rotation, preferably oscillatory rotary movement. The drum is also preferably constructed of 100 non-corrodible sheet metal, and it may be divided into a plurality of interior compartments so as to separate the goods into distinct lots, and facilitate handling and treatment thereof. For this purpose, a partition 105 110

26 extends across the interior dividing it as shown into two separate compartments each of which is provided with a doorway with a closure 27 therefor. The drum is mounted in the tank by means of a swinging supporting frame structure including spaced swinging triangular brackets 28 disposed at either end of the drum and mounted for swinging movement about one apex on a shaft 29 suitably mounted in bearings 30 on the tank frame. The drum 25 is mounted on the free or swinging ends or apices of the brackets 28 by means of a drum shaft 31 extending through the drum and projecting beyond the ends thereof to provide supporting trunnions engaging the brackets. Referring particularly to Fig. 4, it will thus be seen that the receiver drum may be swung upwardly to elevated position as shown in full lines, or downwardly for rotation within the liquor as shown in broken lines.

For raising and lowering the drum, a hoisting mechanism is provided cooperating to swing the end bracket upwardly and downwardly about the shaft 29 as a center. As shown in the drawing the preferred embodiment of the hoisting mechanism includes links 32 connected at their lowered ends to the brackets 28 and at their upper ends to cranks 33 secured to a rotary hoisting shaft 34 mounted in brackets 35 carried by the frame. A worm wheel 36 is fixed on the shaft 34, being preferably enclosed within a housing 36^a and driven by a worm 37 on a shaft 38 driven in turn by a chain belt 39 from a sprocket wheel fixed on a shaft 40. The shaft 40 is arranged to be driven from a power shaft 41 through spur gears 42 and a clutch mechanism 43 arranged for manual control by a hand lever 44 so the shaft 40 may be coupled or uncoupled at will with the shaft 41.

Mechanism is provided for imparting to the receiver drum an agitating movement so as to facilitate through treatment of the fibrous material, and for other purposes appearing hereinafter. This movement may be one of rotation but, for insuring a more thorough treatment and penetration of the fibers, a mechanism for effecting an oscillatory rotary movement is preferably provided. According to the herein disclosed embodiment, the drive embodies an electric motor M connected through spur gears 45 to the power shaft 41 and being controlled for reversal of rotation at intervals by an automatic reversing switch 46 connected for operation from the power shaft 41 through a series of spur gears 47 connected for rotation of the switch shaft 48.

A pair of meshing bevel gears 49 connects the power shafts 29 and 41, and another bevel gear 50 is fixed on the shaft 29 meshing with a similar gear for driving a worm shaft 51 carrying a worm 52 meshing with

a worm wheel 52^a mounted on a shaft 53 extending parallel to the axis of the drum. The worm shaft 51 is supported and enclosed by a combination bracing member and housing 54 extending between shafts 29 and 53 and supported at opposite ends by these shafts. A spur gear 55 is mounted on the shaft 53 meshing with a large drum gear 56 mounted in fixed position at one end of the drum. It will be observed that the shafts 51 and 53 are mounted upon the swinging brackets 28 for movement therewith while the pivotal drive shaft 29 is mounted at the center of oscillation of the brackets and drum.

The operation of the improved mechanism, which will be understood in view of the foregoing disclosure, may be summarized as follows:

The automatic reversing switch 46 operates to change the motor connections at intervals to intermittently reverse the motor M, thus transmitting oscillatory movement through the intermediate power transmission connections to the receiving drum 25. Due to the fact that the drum with its supporting frame is mounted for pivotal movement about the pivotal power shaft 29, it will be observed that the driving mechanism operates with equal facility to rotate the drum in raised, lowered or intermediate position. This is a distinct advantage since treatment of the material may be varied by immersing the drum at different depths in the dyeing liquor, or the drum may be operated when elevated to a position entirely above the liquor effecting among other advantages the drainage of the liquor from the material, and permitting the adjustment of the drum to bring the various compartments into position adjacent the door 20 for loading or unloading the contents of the drum. The drum may also remain in elevated position when loaded with material when for any reason it is desired to keep it for a greater or less period of time from contact with the liquor.

When it is desired to raise or lower the receiving drum when the motor is in operation, it is only necessary to throw the clutch mechanism 43 into mesh by operation of the hand lever 44 when operation of the lifting cranks 33 will be effected through the worm gear 36 and the other connections described. The drum may thus be positioned at any degree of elevation by throwing out the clutch 43 at the proper time, the drum being then supported in such position through the irreversible mechanism provided by the worm wheel 36 and worm 37.

When the receiving drum is in elevated position and one of the drum doors 27 lies in juxtaposition to the front door 20 of the tank, as best shown in Fig. 4, loading or unloading of the drum may then be readily

effected. When the parts are in this position, the doors 20 and 27 are opened and the loading apron 24 swung inwardly to the position shown in broken lines in Fig. 4 5 where it forms in effect a continuation of the interior drum partition 26, whereupon unloading of the material by sliding it over the partition and apron will be a simple matter. The apron aids in a similar manner in loading the drum. It will be understood that the drum may be adjusted to the correct loading and unloading position (Fig. 4) by stopping the motor M at the proper point. The switch 46 may be conveniently arranged 10 for shutting off the motor, and may be employed for jogging the motor to bring the drum to the position desired.

Since the receiving drum may be raised at will by the simple manual operation of throwing in the clutch 43, it will be seen that any change to the condition of the dye bath is greatly facilitated should this become at any time necessary or desirable. For example it often becomes necessary in the 20 treatment of textiles to replenish the liquor or to add more coloring matter to bring the goods up to shade. Furthermore, it is often desirable to bring the treating liquor to a given temperature, such for example as to assure proper solution of the dye in the liquor before immersion of the drum and its contents in the dyeing liquor, this operation being readily accomplished by means of the mechanism described. If boiling of the 30 liquor is indicated this may be done with the drum suspended above the liquor, thus avoiding agitation of the goods under treatment or other damage thereto.

Since certain changes may be made in 40 the above construction and different embodiments of the invention could be made without departing from the scope thereof, it is intended that all matter contained in the above description or shown in the accompanying drawing shall be interpreted as 45 illustrative and not in a limiting sense.

It is also to be understood that the following claims are intended to cover all of the generic and specific features of the invention 50 herein described, and all statements of the scope of the invention which as a matter of language, might be said to fall therebetween.

Having described my invention, what 55 I claim as new and desire to secure by Letters Patent, is:—

1. In a machine for treatment of textiles, in combination, a tank for the treating liquor, a receiver mounted for rotation on a horizontal axis within said tank, means for 60 rotating said receiver, and means connected for operation by said rotating means for lifting the receiver in a plane transverse to said axis from the treating liquor.

2. In a machine for treatment of textiles, 65 in combination, a tank for the treating

liquor, a receiver mounted for rotation on a horizontal axis within said tank, means for rotating said receiver, and means connected for operation by said rotating means for lifting the receiver in a plane transverse to 70 said axis from the treating liquor, said rotating means being also connected for rotating said receiver when in raised position.

3. In a machine for treatment of textiles, in combination, a tank for the treating 75 liquor, a receiver mounted for rotation within said tank, means for rotating said receiver, means connected for operation by said rotating means for lifting the receiver from the treating liquor, and a manually controlled clutch mechanism for connecting and disconnecting said lifting means.

4. In a machine for treatment of textiles, in combination, a tank for the treating 80 liquor, a receiver mounted for rotation within said tank, means for rotating said receiver, means connected for operation by said rotating means for lifting the receiver from the treating liquor, said rotating means being also connected for rotating said receiver 85 when in raised position, and a manually controlled clutch mechanism for connecting or disconnecting said lifting means.

5. In a machine for treatment of textiles, in combination, a tank for the treating 90 liquor, a receiver having an opening and being mounted for rotation within said tank, means for rotating said receiver, means connected for operation by said rotating means for lifting said drum from the liquor, and an apron mounted on the machine for movement into position to communicate with the receiver opening to form a loading or unloading support for the goods.

6. In a machine for treatment of textiles, in combination, a tank for the treating 100 liquor, a receiver having an opening and being mounted for rotation within said tank, an interior partition for dividing the receiver into compartments, means for rotating said receiver, means connected for operation by said rotating means for lifting said receiver from the liquor, and an apron mounted on the machine for movement into position to communicate with said receiver 110 opening to form a loading or unloading support for the goods and when in supporting position forming substantially a continuation of the receiver partition.

7. In a machine for treatment of textiles, in combination, a tank for the treating 120 liquor, a receiver drum mounted for rotation within said tank, swinging supporting members disposed at both ends of said receiver drum and connected thereto for rotatably supporting the same, said supporting members being pivotally connected to said tank and swingable to direct said receiver drum from operative position 125 within the tank into elevated loading and 130

- unloading position, power driven hoisting mechanism including a hoisting link connected to one of said swingable supporting members for raising said receiver drum to 5 elevated position and holding it in elevated loading and unloading position, and driving mechanism for operating said receiver drum both in lowered position within the tank or in elevated loading and unloading position.
- 10 8. In a machine for treatment of textiles, in combination, a tank for the treating liquor, a receiver drum mounted for rotation within said tank, swinging supporting members disposed at both ends of said 15 receiver drum and connected thereto for rotatably supporting the same, said supporting members being pivotally connected to said tank and swingable to direct said receiver drum from operative position 20 within the tank into elevated loading and unloading position, power driven hoisting mechanism including a hoisting link connected to one of said swingable supporting members for raising said receiver drum to 25 elevated position and holding it in elevated loading and unloading position, driving mechanism for operating said receiver drum both in lowered position within the tank or in elevated loading and unloading position, 30 said driving mechanism including a drive shaft disposed at the pivotal connection of said supporting members, and power transmission connections between said shaft and said drum and being carried by said supporting members and swingable therewith.
- 35 9. In a machine for treatment of textiles, in combination, a tank for treating liquor, a receiver, a swinging frame for rotatably supporting said receiver within said tank, a 40 lifting shaft supported above the receiver, lifting links connecting said shaft and receiver for raising and lowering the latter, driving mechanism for rotating said receiver, and driving connections between said driving mechanism and said lifting shaft.
- 45 10. In a machine for treatment of textiles, in combination, a tank for the treating liquor, a receiver, a swinging frame for 50 rotatably supporting said receiver within said tank, a hoisting mechanism for swinging said frame to raise or lower the receiver within the tank, a lifting shaft supported above the receiver, lifting links connecting said shaft and receiver for raising and 55 lowering the latter, driving mechanism mounted on said swinging frame for rotating the receiver in raised or lowered position, and driving connections between said 60 driving mechanism and said lifting shaft.
- 65 11. In a machine for treatment of textiles, in combination, a tank for the treating liquor, a receiver, a swinging frame for 70 rotatably supporting said receiver within said tank, a lifting shaft supported above the receiver, lifting links connecting said shaft and receiver for raising and lowering the latter, driving mechanism for 75 raising the latter, driving mechanism for rotating said receiver, a worm drive for said lifting shaft, and driving connections between said worm drive and said driving mechanism.
12. In a machine for treatment of textiles, in combination, a tank for the treating liquor, a receiver drum mounted for rotation within said tank, swinging supporting members disposed at both ends of said receiver drum and connected thereto for rotatably supporting the same, said supporting members being pivotally connected to said tank and swingable to direct said receiver drum from operative position within the tank into elevated loading and unloading position, power driven hoisting mechanism including a hoisting link connected to one of said swingable supporting members for raising said receiver drum to elevated position and holding it in elevated loading and unloading position, driving mechanism for operating said receiver drum both in lowered position within the tank or in elevated loading and unloading position, and an apron mounted on said machine and being movable to and from position to form a loading and unloading bridge between said tank and said receiver drum when the latter is in elevated position.
- 80 13. In a machine for treatment of textiles, in combination, a tank for the treating liquor, a receiver drum mounted for rotation within said tank and being divided into a plurality of interior receiving compartments, swinging supporting members disposed at both ends of said receiver drum and connected thereto for rotatably supporting the same, said supporting members being pivotally connected to said tank and being swingable to direct said receiver drum from operative position within said tank into elevated loading and unloading position, power driving hoisting mechanism including a hoisting link connected to one of said swingable supporting members for raising said receiver drum to elevated position and holding it in elevated loading and unloading position, and driving mechanism for operating said receiver drum both in lowered position within the tank and in elevated loading and unloading position to bring the different compartments thereof into loading and unloading position, and an apron mounted on said machine and being movable to and from position forming a loading and unloading bridge between said tank and said receiver drum when the latter is in elevated position.
- 85 14. In a machine for treatment of textiles, in combination, a tank for the treating liquor having a supporting frame and an elevated doorway leading thereto, a receiver mounted for movement within the 90
- 110
- 115
- 120
- 125
- 130

- liquor and having a doorway, an apron mounted adjacent the tank doorway and being movable to communicate with the receiver doorway to form a loading and unloading support, and a lifting mechanism for lifting the receiver into position so its doorway may assume a position in juxtaposition to the elevated doorway of the tank.
15. In a machine for treatment of textiles, in combination, a tank for the treating liquor having a supporting frame and an elevated doorway leading thereinto, a receiver mounted for movement within the liquor and having a doorway, an apron mounted adjacent the tank doorway and being movable to communicate with the receiver doorway to form a loading and unloading support, a lifting mechanism for lifting the receiver into position so its doorway may assume a position in juxtaposition to the elevated doorway of the tank, and a partition dividing the receiver into compartments, and forming substantially a continuation of the supporting apron when the latter is in supporting position.
16. In a machine for treatment of textiles, in combination, a tank for the treating liquor, a receiver drum mounted for rotation within said tank and being divided into a plurality of interior receiving compartments, swinging supporting members disposed at both ends of said receiver drum and connected thereto for rotatably supporting the same, said supporting members being pivotally connected to said tank and being swingable to direct said receiver drum from operative position within said tank into elevated loading and unloading position, power driving hoisting mechanism including a hoisting link connected to one of said swingable supporting members for raising said receiver drum to elevated position and holding it in elevated loading and unloading position, and driving mechanism for operating said receiver drum both in lowered position within the tank and in elevated loading and unloading position to bring the different compartments thereof into loading and unloading position.
17. In a machine for treatment of textiles, in combination, a closed tank for the treating liquor, a receiving drum mounted for rotation within said tank in lowered position in the treating liquor or in elevated position, an operating mechanism for rotating said receiver drum in either raised or lowered position, and an apron mounted on said machine and being movable to and from position to form a loading and unloading bridge between said tank and said receiver drum when the latter is in elevated position.
18. In a machine for treatment of textiles, in combination, a closed tank for the treating liquor, a receiving drum mounted for rotation within said tank in lowered position in the treating liquor or in elevated position within the closed tank, and cooperating doorways in the tank and drum assuming juxtaposition when the drum is elevated.
19. In a machine for treatment of textiles, in combination, a tank for the treating liquor having a supporting frame and being closed, a receiving drum mounted for rotation within said tank in lowered position in the treating liquor or in elevated position within the closed tank, an operating mechanism for rotating said receiver drum in either raised or lowered position, cooperating doorways in the tank and drum assuming juxtaposition when the drum is elevated, and a partition for dividing the interior of said drum, being positioned adjacent the doorway thereof to support the goods under treatment for convenient removal thereof through said doorways or to initially receive said goods when the drum is in raised position.
20. In a machine for the treatment of textiles, in combination, a substantially closed tank for the treating liquor, a receiving drum mounted for being elevated and lowered within said tank and rotatable in either elevated or lowered position within the tank, said tank being elongated in vertical dimension so as to permit elevation of the receiver drum and to house the latter when in elevated position, cooperating receiving and discharge doorways in said tank and receiver drum assuming juxtaposition when the drum is elevated, an operating mechanism for rotating said receiver drum in lowered position in the treating liquor or for rotating it in elevated position so as to bring the said doorways into cooperating relation to permit convenient charging of the receiver drum or to discharge the contents of said drum, an interior partition for said drum positioned adjacent the doorway thereof so as to support the goods for removal when said doors are in cooperative position and an apron mounted on said machine and being movable to and from position substantially in alignment with said interior partition to form a loading and unloading bridge between said tank and receiver drum when the latter is in elevated position.

In testimony whereof I affix my signature.

WILLIAM E. H. BELL.
